HANDLE FOR A SURGICAL INSTRUMENT OR THE LIKE

Thomas Lamb, Mariomi Road, New Canaan, Conn.

Filed Oct. 1, 1959, Ser. No. 57,748

Term of patent 14 years

(Cl. D22—3)

Figure 1 is an elevational view of one side of a handle for a surgical instrument or the like embodying my new design.

Figure 2 is a top plan view.

Figure 3 is a bottom plan view.

The conventional portions of a surgical instrument shown in dotted lines in Figures 1, 2 and 3 are only for the purpose of illustration.

I claim:

The ornamental design for a handle for a surgical instrument or the like, substantially as shown and described.
